GAETANO DI GIOVANNI, OF NEW YORK, N. Y., ASSIGNOR OF ONE-HALF TO JULIUS HAMMER, OF NEW YORK, N. Y.

BURGLAR-ALARM.

1,031,535.

Specification of Letters Patent.

Patented July 2, 1912.

Application filed April 4, 1910. Serial No. 553,172.

To all whom it may concern:

Be it known that I, GAETANO DI GIOVANNI, a subject of the King of Italy, and a resident of the city of New York, borough of the Bronx, in the county and State of New York, have invented a new and Improved Burglar-Alarm, of which the following is a full, clear, and exact description:

My invention relates to burglar alarms, my more particular purpose being to provide an electric alarm associated with a number of cords so arranged that the cutting of any cord, or the stretching of any cord, as the case may be, will cause the electric alarm to be actuated.

More particularly stated, I provide a number of cords, separated from each other, and for some purposes independent, and connect with each cord a contact mechanism so arranged that a slackening or a tightening of the cord will cause the contact mechanism to close an electric circuit.

Reference is to be had to the accompanying drawings forming a part of this specification, in which similar characters of reference indicate corresponding parts in all the views.

Figure 1 is a fragmentary view, showing my burglar alarm as applied to a window: Fig. 2 is an enlarged section, showing certain details as to the mounting of the cords and their connection with the contact mechanism; and Fig. 3 is a diagram of the wiring.

A wall 4 is provided with a window, door, or the like, 5. For convenience, I will designate this part hereinafter as a window. A roller 6 is provided with a spiral spring 7, and is mounted upon brackets 8, the latter being secured upon a small shelf 9, immediately above the window. The roller 6 and its associated parts constitute merely an ordinary type of spring roller such as is used for instance, in connection with rolling curtains. A number of cords 10 are separately connected with the spring roller 6, and depend through holes 11 in the shelf 9. A rod 12 is connected with the lower ends of all of these cords. This rod carries rings 13, which may be brought into engagement with staples 14, or other fastening mounted below the window. By drawing the rod 12 directly downward, and bringing the rings 13 into engagement with the fastenings 14, the various cords 10 may be kept taut.

At 10^a, 10^b, are shown two of the cords, the cords 10^a being cut or broken, and the cord 10^b being stretched as might happen, if a burglar should undertake to pass through the window.

Mounted upon the shelf 9 are a number of metallic brackets 15, and journaled upon each of these brackets by aid of a pivot pin 16^a is a contact lever 16, having generally the form of a bell crank. Under each contact lever is a spring 17, which tends to raise the lever. Extending above the window 5 is a bar 18, and mounted upon the latter are a number of contact buttons 19, so arranged that when the contact levers 16 rise in consequence of the pressure of the springs 17 under them, the contact levers are brought into engagement with the contact buttons 19.

At 20 are a number of contact buttons each being disposed directly under one of the contact levers 16. Each contact lever 16 is provided with an eye 21, and each cord 10 is threaded through one of these eyes. Each cord 10 is further provided with a bead or knot 22 which engages the eye 21 with which it is associated. By this arrangement, whenever one of the cords is pulled directly downward, so that the bead or knot 22 presses upon the eye 21, the contact lever 16 associated with that particular cord is rocked, and thus brought into engagement with the contact button 20, also associated with that particular cord. When one of the contact levers 16 is depressed by the tightening of its cord, its eye is drawn down as at 21^a, and when one of the cords is relaxed or broken, the contact lever affected thereby is raised so that its eye 21^b appears as indicated.

A battery is shown at 23, and connected with the latter is a wire 24. An alarm bell is shown at 24^a, and with the latter is connected a wire 24^b. Joining this wire are two other wires 25, 26, which extend along the shelf 9. Connected with each wire 25 are a number of short wires 27, leading respectively to the contact buttons 19. Connected with the various contact buttons 20 are short wires 28, all of which are connected with the wire 26. The various contact levers 16 are connected by wires 29 with another wire 30, the latter leading to a hand switch 31. This hand switch is connected by a wire 32 with the battery 23. Any number of bells 24^a may be employed.

and these bells may be disposed in different locations for the purpose of giving alarm simultaneously. For instance, one bell might be located on the street, one in the quarters of the watchman or janitor, and one in a private detective agency. So, also, any number of pairs of wires 25, 26 may lead to these bells, there being, if desired, a separate pair of wires to each button 19, 20. Since the wiring may be done in a variety of ways and I do not wish to be limited to any particular wiring, I do not consider it necessary to describe these various forms.

15 The operation of my device is as follows: I will suppose that a window has been equipped with the various parts above described, as indicated in Fig. 1. Suppose, now, that a burglar undertakes to enter this window. He may succeed in raising the sash, but in an effort to enter the room he is very likely to break some of the cords and to subject others to unusual tension. For instance, as indicated in Fig. 1, the cord 10^a 25 is broken and the cord 10^b is unduly stretched. In breaking any one of the cords, he necessarily slackens its upper portion, and the contact lever 16 with which it is associated being thus freed from the pressure of its bead or knot 22, rises in consequence of the upward pressure of the spring 17. The contact lever 16 thus affected is, therefore, brought into engagement with its contact button 19. The following circuit 30 is thus completed: battery 23, wire 32, switch 31, wire 30, one of the wires 29, one of the contact levers 16, one of the contact buttons 19, one of the wires 27, wire 25, wire 24^b, bell 24^a, wire 24, back to battery 23. 35 This rings the bell, and of course creates an alarm. Suppose, however, that for any reason the breaking or cutting of the cord 10^a failed to produce the effect just described, the cord 10^b being unduly stretched, as indicated in Fig. 1, causes its corresponding contact lever 16 to be drawn downwardly, and into engagement with its contact button 20. The following circuit is thus completed: battery 23, wire 32, switch 31, wire 50 30, one of the wires 29, the corresponding contact lever 16, its contact button 20, the corresponding wire 28, wires 26 and 24^b, bell 24^a, and wire 24 back to battery 23. It thus happens that the stretching of the cord 10^b 55 will sound the alarm as well as the slacken-

ing of the cord 10^a, due to its being cut or broken.

For convenience I show only an electric bell; as a means of giving the alarm. It will be understood that I do not limit myself thereby, as in the present state of the art, the ringing of an electric bell is merely the equivalent of any other arrangement for giving an alarm. Neither do I limit myself to the particular arrangement of the several parts as shown, nor to the employment of the circuit precisely as described.

It will be noted from Figs. 1 and 3, that when the bar 12 is drawn down, and secured, the various contact levers 16 are in suspension as it were, each contact lever being out of engagement with its contact buttons 19 and 20, but liable to be brought into engagement with its button 19 by the relaxation of the particular cord associated with the contact lever affected, and also liable to be brought into engagement with the contact button 20 associated with that particular cord when the latter is unduly tightened.

Having thus described my invention, I claim as new and desire to secure by Letters Patent:

The combination of a roller, cords connected to and adapted to be wound upon the said roller and having knotted enlargements at equal distances from their said connected ends, a bell crank lever for each cord having an apertured horizontal arm through the aperture of which the cord is threaded in a downward direction with its said enlargement above the said arm, a spring bearing against said lever and tending to move the same in an upward direction, contact buttons disposed in the paths of movement of said lever in opposite directions, means to sound an alarm when said lever contacts with either of said buttons, a bar to which the lower free ends of the cords are attached, and means to detachably secure said bar in a position adapted to maintain the bell crank levers free of their contacts.

In testimony whereof I have signed my name to this specification in the presence of 105 two subscribing witnesses.

GAETANO DI GIOVANNI.
